BUFFING OR POLISHING WHEEL

Albert S. Yohe, Jersey City, N. J., assignor to The Bias Buff & Wheel Company, Inc., New York, N. Y., a corporation of New York

Application February 1, 1934, Serial No. 709,342

4 Claims. (Cl. 51—193)

This invention relates to buffing or polishing wheels, and more particularly to that type thereof—described and claimed in Letters Patent No. 1,298,522, dated March 25, 1919 (reissued November 15, 1921, No. 15,226) and No. 1,404,620, dated January 24, 1922—in which an annular wheel, or wheel unit or section, having a plurality of superimposed layers or plies is made up from a strip of cotton or other textile material, preferably cut on the bias, doubled up widthwise and gathered on its folded median line around and to form a central opening.

I have discovered that I can greatly improve these wheels, in which the puckers formed in the plies around the central opening by the gathering of the folded inner edge of the doubled strip extend only a short distance out therefrom and leave the outer portions of the plies flat, by further gathering the strip—for example, by gathering it along its median line with a row of stitches before it is folded, so that there will be formed in the plies radial pleats which extend outwardly to and are present in their peripheries, the pleats thus formed serving not only to give to the plies a ruffled effect which increases the peripheral or working face of a unit having a given number of plies but also to provide pockets therein to receive and hold a buffing composition.

The invention will be understood by reference to the accompanying drawing, illustrating one practical embodiment thereof, in which—

Figure 1 is a plan view of a broken length of the strip of fabric from which the wheel unit or section is formed, showing it as gathered along its median line; Fig. 2 is a perspective view of the gathered strip wound upon itself to provide the plurality of superimposed layers or plies and partially contracted and doubled and somewhat further gathered on its median line; Fig. 3 is a face or side view, partially broken away, of the completed wheel unit or section equipped with a hub; and Fig. 4 is a peripheral face view of the wheel unit or section.

Referring to the drawing, the strip of material 5, which may be of any suitable material but is preferably of cotton cloth or other textile fabric cut on the bias, is evenly gathered along its median line 6 by a row of stitches made thereat on any suitable machine. The strip so gathered is wound upon itself a sufficient number of times, as heretofore, to provide the required number of superimposed plies in the finished wheel unit or section, and then the rolled strip is contracted and further gathered and folded on its median line around a central opening to form the wheel

unit or section and is or may be secured by a cord 8—an operation which can be conveniently performed by means of the apparatus described and claimed in Letters Patent No. 1,296,409, dated March 4, 1919. For greater security, however, a steel ring is preferably substituted for the tie-cord 8, as has commonly been the practice in the commercial manufacture of wheels of this type, the ring (not shown) being inserted in place after the rolled strip has been doubled and gathered by temporarily bringing the ruffled plies on one side out to cylindrical form and slipping the ring thereon. The unit or section thus formed and with its ruffled plies is then completed either by a hub 9, preferably of cardboard, around which the folded median line of the strip may be gathered and which is secured in place between two fabric disks 10 (one only shown) by circular rows of stitches 11 and 12, or, if a hubless wheel with open center is desired, merely by the single circular row of stitches 12. For use, the units provided with hubs are mounted, separately or in multiple, on a spindle between two compression disks, and the hubless units are similarly mounted between the disks of a special hub providing means for holding the units accurately centered thereon.

The ruffling of the plies not only increases the working peripheral face of the wheel and provides pockets therein to receive and hold a buffing composition, as hereinabove stated, but also possesses other advantages. Wheels of small diameters, made from a soft cloth, are ideal for the coloring or final polishing operation of all classes of work, while those of the larger diameters, made of a hard cloth, work well on automatic buffing machines where the burning of the buffs is likely, since the openness of its working face allows a greater circulation of air which by the ventilation provided serves to prevent or reduce the likelihood of burning. Moreover, the section and density of the wheel required for meeting various shop practices correctly can be accurately regulated merely by varying the degree and/or character of the initial gathering of the strip to thereby vary as desired the extent and width of the pleats formed in the ruffled plies.

It will, of course, be understood that the invention can be variously modified in its several details, within the scope of the appended claims, without departing from the spirit or sacrificing the substantial advantages thereof.

What I claim as new, and desire to secure by Letters Patent, is—

1. The process of making an annular buffing or

- polishing wheel unit having a plurality of ruffled plies of textile material with radial pleats extending from a central opening outwardly to and present in their peripheries, which comprises first 5 gathering a strip of the material with a row of stitches along its median line and then folding the gathered strip widthwise on such median line and further gathering the folded edges of a plurality of superimposed windings of the doubled 10 strip around and to form the central opening.
2. The process of making a buffing or polishing wheel unit with ruffled plies, which comprises gathering a strip of suitable material along its median line, then rolling the gathered strip upon 15 itself to provide the number of plies required in the unit, and afterwards folding the gathered and wound strip and further gathering it on its median line around and to form a central opening.
3. The process of making an annular buffing or 20 polishing wheel unit having a plurality of superimposed ruffled plies of textile material with ra-

dial pleats therein extending from a central opening to and present in the periphery, which comprises suitably gathering a strip of the material along its median line, then rolling the gathered strip upon itself to provide the required number of plies, and afterwards doubling up widthwise and further gathering the gathered and wound strip on its median line around and to form a central opening. 5

4. An annular buffing or polishing wheel unit 10 having a plurality of ruffled plies of textile material with radial pleats extending from a central opening outwardly to and present in their peripheries, said plies consisting of a strip of material first gathered with a row of stitches along its median line and then doubled widthwise thereon and further gathered in superimposed windings presenting the gathered and folded edge to and around the central opening. 15
